(57) **CLAIM**

The ornamental design for a slider for articles of jewelry, as shown and described.

DESCRIPTION

FIG. 1 is a perspective view of an embodiment of the slider for articles of jewelry of the subject disclosure;

FIG. 2 is a front elevation view of the slider for articles of jewelry of FIG. 1;

FIG. 3 is a rear elevation view of the slider for articles of jewelry of FIG. 1;

FIG. 4 is a top plan view of the slider for articles of jewelry of FIG. 1;

FIG. 5 is a rear plan view of the slider for articles of jewelry of FIG. 1;

FIG. 6 is a left side elevation view of the slider for articles of jewelry of FIG. 1; and

FIG. 7 is a right side elevation view of the slider for articles of jewelry of FIG. 1;

FIG. 8 is a view of an embodiment of an article of jewelry including the slider for articles of jewelry of FIG. 1

FIG. 9 is a perspective view of an embodiment of the slider for articles of jewelry of the subject disclosure;

FIG. 10 is a front elevation view of the slider for articles of jewelry of FIG. 9;

FIG. 11 is a rear elevation view of the slider for articles of jewelry of FIG. 9;

FIG. 12 is a top plan view of the slider for articles of jewelry of FIG. 9;

FIG. 13 is a rear plan view of the slider for articles of jewelry of FIG. 9;

FIG. 14 is a left side elevation view of the slider for articles of jewelry of FIG. 9; and

FIG. 15 is a right side elevation view of the slider for articles of jewelry of FIG. 9; and,

FIG. 16 is a view of an embodiment of an article of jewelry including the slider for articles of jewelry of FIG. 9.

The broken lines shown in the drawings do not form part of the claimed design.
